UNITED STATES PATENT OFFICE.

HENRY A. BODWELL, OF ANDOVER, MASSACHUSETTS, ASSIGNOR TO SMITH & DOVE MANUFACTURING CO., OF ANDOVER, MASSACHUSETTS, A CORPORATION OF MASSACHUSETTS.

WINDING CORDAGE.

Application filed August 9, 1924. Serial No. 731,076.

To all whom it may concern:

Be it known that I, HENRY A. BODWELL, a citizen of the United States of America, and resident of Andover, in the county of 5 Essex and State of Massachusetts, have invented new and useful Improvements in Winding Cordage, of which the following is a specification.

This invention relates to winding cordage 10 and to a wound mass or package of cordage adapted to be evenly unwound from its interior layers outwardly.

In a preferred form the cordage package or mass may be of any cross-wound type, 15 such as a ball, cheese or cop characterized by self-sustaining structure comprised of the cordage itself. The cordage referred to in this specification comprises any filament or association of filaments whatever such as, 20 for example only, spun, laid, twisted or braided yarns, cords or twines, sewing threads, rope, wire or wire-rope, strips, tapes or braids.

The well-known forms of packages made 25 by winding with quick-pitch axial or surface traverses on a cylindrical or conical support, producing a ball, cheese or cop having the so-called Fiji, Wardwell or "Universal" wind, is convenient for most uses, 30 comprising a self-sustaining mass in which each layer of accretions of the winding cordage consists of many runs of the cordage extending in the axial direction from one end to the other end of the package, 35 which is cylindrical or frusto-conical, the ends transverse to the axis being comprised of the cusps at reversals of the runs of the component spiral elements severally building up into each layer. When interiorly 40 supported by a headless tube, cone or quill, as in usual practice, such yarn packages are of ancient and approved use, having the quality of evenly unwinding from their exterior end or side faces without weakening 45 the structure of the remainder of the winding.

But there are many situations in which it is advantageous to provide for unwinding cordage of the kind referred to from the 50 interior outward; for example, for the purpose of preventing tangling or ballooning,

or in order to permit the cordage packages to be unwound from cells or containers little or no larger than the wound package without substantial variation of tension from part to part of the unwinding operation; or to provide for unwinding several balls or masses joined together in tandem from within the same container. A ball or package capable of unwinding from 55 within which shall also have the structural and other advantages of the quick-traverse cross-wound structure is thus highly desirable. The ordinary traverse-, cross-, or Fiji-wound package when its core, tube or quill is withdrawn to permit unwinding from within is not suitable for these purposes because its structure is such as then to permit the whole wound mass to be broken across, or to be extended lengthwise 60 with loss of compact solidity, respectively by breaking stresses acting crosswise of the axis of wind, or tensile stresses acting along the axis. These qualities of the wound packages prevent their commercial use 65 effectively, too large a proportion of such unsupported packages being so deformed before use, in making or in shipment, as to prevent unwinding from within with the necessary regularity and freedom from 70 snarls. In large fields of use, such as for twine packages for wrapping or bundling, and particularly for the supply of twine for harvester binders, there is little or no use 75 of this described type of package for the 80 mentioned reasons.

This invention therefore has among its objects to provide a cordage package or wound mass for interior unwinding free from these disabilities at no substantial increase of cost, as well as an art of making 85 this article of manufacture and apparatus for practicing the method or art.

The invention will be explained in connection with one exemplification only of the 90 article, method and apparatus as shown in the accompanying drawing, in which:

Fig. 1 is a transverse section through the center of a cordage package embodying the present invention;

Fig. 2 is an elevation of a cordage package, the outer layers being broken away;

Fig. 3 is a front elevation of a suitable old winding machine showing simple apparatus for carrying out this method;

Fig. 4 is a side elevation of a feeding guide; and

Fig. 5 is a detail transverse section on the line 5—5 of Fig. 4.

The cordage package A, Figs. 1 and 2, may be made up of a plurality of cross-wound or Fiji-laid layers of relatively steep angular pitch, the spiral runs being reversed at the ends of the layers as usual, as at r , Fig. 2. In the form shown cusps or reversals r of the layers appear at the end surfaces of a cylindrical package, the yarn concerned coming to view presently at the other end of the package. Thus a relatively rigid, self-sustaining package may be made from which the yarn is unwound from the inner or central layers. The cordage package may have any desirable relation of length to diameter, and may be conical, ovoid or spherical, if desired, but in any form is characterized by layers of windings of relatively quick-pitched traverses.

Machines for winding yarn for making such cordage masses are well known, a machine for this purpose of one of the types in large present use being indicated in broken lines in Fig. 3. Such machines ordinarily include a winding spindle 1 upon which the yarn is wound as laid by the traverse guide 2 for the spiral or cross layers, the cam 3, for example, reciprocating the traverse guide 2 perpendicular to the plane of Fig. 3 in relation to the rotation of spindle 3.

It will be understood that the spindle 1 is adapted to provide a temporary support during winding only, the wound package being removed when complete. Instead of providing an interior tube or cone to support the doffed package, it is herein provided that the package shall contain one or more flexible reinforcing inclusions held in place by being caught between adjacent layers of the cordage. Preferably these inclusions are nearly but not quite coextensive with the axial length of the package, only a few thousandths of an inch in thickness, and circumferentially discontinuous, so that when uncovered upon unwinding, the reinforcing inclusions are left free and will not disturb further unwinding. For these purposes a suitably shaped sheet of thin, tough and flexible paper is preferred as shown at B. These should be of such a width as to nearly cover the axial width of a cordage layer, and such length as nearly to cover the circumferences of the winding cylindrical mass when applied to layers near the exterior of the winding mass. For a cylindrical package, the sheets of paper at B are preferably rectangular. As shown at b the first applied reinforcement may overlap on being wrapped about the forming winding.

In the preferred way of making the package A, the inclusions B are applied by one edge to the winding mass whereupon the winding cordage wraps the flexible sheet about the layers previously laid, and succeeding runs of the cordage bind down and complete the positioning of the sheet inclusion B. This may be done by hand or the operation of suitable devices. A preferred way of performing the operation is to provide a guide 4 associated with the winding spindle in such a way that an inclusion B fed through the guide by hand or gravity comes into contact with the surface of the package at the nip or place of contact of the winding run of cordage and the previously laid surface. The guide 4 may be suitably supported so that its lower end lies in such relation to any surface concentric with spindle 1 as to accomplish this. For example, a guide 4 of suitable length is pivoted at 7 on any suitable attachment to the winding machine, such as a member of a frame bearing a horizontal member 5 and an upright 6. The lower end of guide 4 thus rests on the winding surface and moves on an arc passing near the axis of spindle 1, and clearing the locus of motion of traverse guide 2. The leading edges of the inclusions, layers or sheets of material B drop into the nip between guide 2 and the winding surface, to be caught and held by the cordage t as the rotation of the winding mass draws the paper or other inclusion B from the guide 4. Sheets B may be fed to the forming cordage mass at intervals of a predetermined number of revolutions of the winding spindle if desired, so that they may be accordingly spaced in the finished package to provide resistance to tensile strains. Sheet feeding devices of any desired type may be used for feeding the sheets B to the guide 4, but manual feeding is effective for the purpose.

A cordage mass or package provided with the layer or layers B is not subject to the objections inherent in cross-wound packages. Such a reinforced package effectively resists all breaking or tensile strains tending to distort it from its original condition, and is capable of unwinding uninterruptedly, the discontinuous flexible sheets B going free without snarling the unwinding run of cordage when unlocked by unwinding.

It will be observed that the circumferential discontinuity of the inclusions B is useful to permit the cordage of a layer, as at b^2 , Fig. 2, to pass above and exterior to the reinforcement at any axial position of the winding run of cordage at the time when the edge of the inclusion B may be placed on the winding mass.

Since the packages are intended for inside unwinding, it is desirable to prepare the outer layer to resist slackening. For

this purpose the end of the yarn or twine or other cordage may be tucked under a previous run, as usual, at x , and the reversal cusps of the last few yarns laid are 5 preferably fastened down. A preferred way of doing this is to provide, as indicated by the shaded area w a stiffening of some adhering and penetrating substance of a harmless nature adapted also to stick 10 together the adjacent runs of the cordage. A dab of hot wax or paraffin applied with a brush at the two points at each end of the package is preferred and recommended for this purpose.

15 I claim:

1. A wound cordage package adapted to be unwound from within having therein a reinforcing inclusion held between the windings and adapted to maintain the relation 20 of the windings against distorting stresses.

2. A self-sustaining axially perforate cordage mass of wound layers having an inclusion of flexible material held between the windings and adapted to maintain the 25 package against separation of its windings in an axial sense.

3. A cordage package comprising traverse-wound layers forming a structure adapted to be unwound from the center 30 thereof, and having a circumferentially discontinuous sheet of flexible material inserted between the windings.

4. A wound package of cordage having a plurality of layers and adapted to be unwound from the inner layer, comprising one or more sheets or paper inserted between the windings, the sheets of paper 35 constituting a reinforcement against tensile axial stresses tending to distort the applied form of the wound layers.

5. A cordage package comprising a plurality of traverse-wound layers of relatively steep angular pitch, and having a flexible and thin sheet of material interposed between the windings, said sheet being shorter than the extent of the effective winding 45 traverse.

6. A self-sustaining cordage package for inside unwinding built up of traverse-wound layers, the exterior layer having the last few runs only of winding fastened together at the ends of the package to hold them in place in use.

55 7. A self-sustaining cordage package for inside unwinding built up of traverse-wound layers and having an interior rein-

forcement against separation axially, the exterior layers having the reversal cusps of the last few runs only of the traverse wind of the exterior layer stuck together by 60 a locally-applied adhesive substance.

8. In a cordage winding machine having a winding spindle and means for directing the winding of the yarn in layers on the spindle to produce a self-sustaining package, means in combination therewith for guiding a piece of flexible sheet material into winding contact between the winding mass on the spindle and the cordage winding thereon.

70 9. In a cordage winding machine, a winding spindle and a gravity sheet-feeding guide in juxtaposed relation to the spindle adapted to position a sheet of material with its leading edge in juxtaposition to the surface of the winding mass, and between said surface and the winding run of cordage.

75 10. A winding machine having in combination means for rotating a winding mass, a traverse guide for laying a run of cordage on the surface of said mass to produce a self-sustaining package, and a guide for delivering the leading edge of a blank of sheet material into contact with the surface of said mass and between said surface and said run of cordage.

80 11. In a cordage winding machine, a pivoted sheet feeding guide having a delivery orifice in one depending end and means for supporting the delivery orifice 90 of said guide in juxtaposition to an element of the surface of the winding mass of cordage with freedom of motion about its pivotal axis in a radial direction in respect to the winding mass.

95 12. Art of making self-sustaining inside-unwinding wound packages of cordage comprising as a step causing a flexible sheet of material continuous in the axial direction 100 of the package to be included between successive layers of the winding cordage.

13. Art of making self-sustaining inside-unwinding wound packages of cordage comprising as steps causing a flexible sheet of material continuous in the axial direction 105 of the package to enter the winding mass between the surface of an intermediate layer and a run of cordage comprised in a succeeding layer.

110 Signed by me at Andover, Massachusetts, this first day of August, 1924.

HENRY A. BODWELL.
